UNITED STATES PATENT OFFICE.

IRA A. WEAVER, OF SPRINGFIELD, ILLINOIS, ASSIGNOR, BY MESNE ASSIGNMENTS, TO
INTERNATIONAL HARVESTER CORPORATION, A CORPORATION OF NEW JERSEY.

CORN-PLANTER.

1,144,625.

Specification of Letters Patent. Patented June 29, 1915.

Application filed August 9, 1907. Serial No. 387,873.

To all whom it may concern:

Be it known that I, IRA A. WEAVER, a citizen of the United States, residing at Springfield, in the county of Sangamon and State of Illinois, have invented certain new and useful Improvements in Corn-Planters, of which the following is a specification.

My invention relates to seed planters, and the object is to improve and simplify the construction and operation of such devices. In the carrying out of this object I have employed intermittently operating driving mechanism receiving fixed movements, and connecting means between the driving mechanism and the seed dropping elements for varying the distance through which the latter are driven at each actuation of the intermittent mechanism. The number of kernels or seeds planted in each hill may thus be varied without disturbing the seed plates or dropping elements. The adjustment of the connecting mechanism may be controlled from the driver's seat so that changes may be made in the quantity of seed dropped during the progress of the machine over the field. Moreover, the construction shown is such that different numbers of seeds may be planted at each side in a two-row machine.

The planter shown is a combined check row and drill type of an improved form. In the check row operation the seed shaft is driven intermittently, the initial movement being imparted by means of check forks contacting with tappets on a check wire, and the movement completed by power derived from the axle or ground wheel. In the drilling operation the seed shaft is driven constantly, and the connecting mechanism may then be employed, if desired, to interrupt the movement of the seed plates so that an intermittent drilling is thereby obtained.

Other objects and advantages will become apparent upon a fuller understanding of the invention.

In order that those skilled in the art may fully understand my invention, I have illustrated one form of my improved planter on the accompanying drawings, forming a part of this specification, wherein—

Figure 1 is a perspective view of the planter showing the pole or tongue broken off; Fig. 2 is a plan view on an enlarged scale of one of the planting or seed drop-

ping mechanisms; Fig. 3 is a front elevation of the mechanism shown in Fig. 2; Fig. 4 is a perspective view of one of the seed dropping or feeding devices with parts broken away and with the seed reservoir thrown back; Fig. 5 is a vertical section on a curved line 5—5 of Fig. 2; Fig. 6 is a plan view of a portion of one of the seed dropping mechanisms showing the seed receptacle or reservoir and seed plate turned backwardly on their pivot or hinge pin, revealing the mechanism normally beneath these parts; Fig. 7 is a vertical cross section on line 7—7 of Fig. 6, the parts being in operative position; Fig. 8 is a perspective view of the pawl controller, the pawl forming a part of the clutch mechanism between the pinion driving the seed plate and the main actuating shaft; Fig. 9 is a substantially-central cross-section on a line 9—9 at right angles to line 7—7 of Fig. 6; Fig. 10 is a perspective view of the ring or holder for the seed plate; Fig. 11 is a longitudinal section of the ring or holder with the seed plate seated therein. Fig. 12 is an elevation of the mechanism shown in Fig. 2 as viewed from the left-hand end; Fig. 13 is a perspective view of one of the clutch pawls; Fig. 14 is a vertical cross-section on line 14—14 of Fig. 2; Fig. 15 is a substantially-central vertical section through the valve or seed dropping mechanism, certain portions being left unsectioned; Fig. 16 is a view similar to Fig. 15 showing the valve mechanism in condition for drilling; Fig. 17 is a horizontal section on line 17—17 of Fig. 12; Fig. 18 is a horizontal section on line 18—18 of Fig. 12; and Fig. 19 is a cross-section on line 19—19 of Fig. 12. Figs. 20 to 24, inclusive, illustrate the pawl and ratchet clutch and its actuating mechanism in various positions.

As shown in Fig. 1, my improved planter includes, besides suitable frame work and other parts, the ground or carrying wheels 20, 20, their axle 21, a pair of seed reservoirs or compartments 22, 22, and a single transverse shaft 23 extended across the front of the machine and rotatable in the bearings 24 supported by the frame of the machine. At each end shaft 23 is equipped with a fork 25, the bifurcated end of which is adapted to straddle a check row wire (not shown) and be actuated by its tappets

or buttons, the wire being guided on either side of the machine by a pair of rollers 26 and 27 at right angles to each other, as is customary.

5 Near the middle of shaft 23 and mounted loosely thereon is a casting 28 (Figs. 2, and 3,) equipped at one end with a sprocket wheel 29 and at its other end with a ratchet site the top portion of flange 34, as is clearly 10 illustrated in Fig. 14. The casting 28 and its integral ratchet wheel 30 are constantly rotated during the travel of the planter by means of a sprocket chain 31 (Fig. 1) which passes around the sprocket wheel 29 and a 15 similar wheel (not shown) on axle 21. Adjacent to ratchet 30 and fixed to shaft 23 by one or more set screws 32 (Fig. 14) so as to rotate therewith is a casting 33 having on its face toward ratchet 30 a substantially right-angle flange 34 which at its 20 lower end terminates in a curved flange or pocket 35 adapted, under certain conditions, to receive and accommodate a roller 49 hereinafter mentioned. This casting 33 also 25 has a stop 36 integral therewith and opposite the top portion of flange 54, as is clearly shown in Fig. 14. Pivoted to casting 33 at the point 37 is a bell-crank pawl 38 (Fig. 13) having a hardened-steel portion or tooth 39 adapted to overlie and engage the teeth of ratchet 30 and a depending arm or tail 40. This pawl also has on its top surface a curved lug or projection 41 adapted to lie within a spring 42 located between the 35 pawl and casting 33 and tending to push the pawl into operative engagement with the ratchet teeth.

Bolted to the frame of the machine at 43 is a casting 44 having a pair of inwardly-extended legs 45 and 46 which are apertured in alinement to receive and hold in fixed position a cylindrical rod or shaft 47 which extends some distance beyond the leg 46, as shown in Fig. 2. An arm 48 which 45 may be of considerable weight if desired has at one end a roller 49 adapted to cooperate with the flange 34 and the lower end of pawl-tail 40 and has a main hollow body 50 with two legs 51 and 52 slidable 50 and rotatable on the rod or shaft 47, leg 51 being located between the legs 45 and 46, while the other leg 52 is outside of arm or leg 46. A spring 48^a see Fig. 14 fastened to arm 48 and the frame of the 55 machine normally pulls the arm downwardly. Housed within the member 50 and encircling rod 47 I provide a coil spring 53 which at one end abuts against the arm 46 and at its other end against a handle 54 loosely mounted on the rod and located in a slot 55 of the member 50 just inside of arm 51. Spring 53 therefore tends to keep arm 48 and roller 49 in the position shown in Fig. 2. Upstanding from the top of the casting 60 is a lug 56 with which the arm or lever

54 cooperates to prevent substantial shifting of the body 50 when the arm 48 is thrown to one side into the path of the lug.

Casting 28 (Figs. 3) and its attached ratchet 30 rotates constantly, receiving its 70 power from the axle of the ground wheels, while shaft 23 is rotated only intermittently when given an initial movement by a tappet or button of the check wire striking one or the other of the forks 25. Under 75 normal conditions the pawl 38 is out of engagement with the ratchet teeth 30, being held in this position, as indicated in Fig. 14, by the roller 49 of arm 48. As soon as one of the tappets of the check wire 80 strikes one of the forks, shaft 23 is partially rotated thereby sufficiently to free the casting 33 which turns therewith and arm 40 of the pawl from the roller 49, see Figs. 23 and 24, the roller passing under the tail 40, whereupon under the influence of spring 42, pawl 38 engages one of the teeth of the ratchet, thereby forming an operative connection between the constantly rotating ratchet wheel 30 and shaft 23. This latter 90 shaft now receives its rotation from the axle 21 of the ground wheels 20 through the chain 31, sprocket wheel 29, casting 28, ratchet 30, pawl 38, and casting 33, the completion of the rotation of shaft 23 and its 95 attached forks, after it has been started by the tappet or button of the check row wire, being accomplished or carried out by this mechanism, and not by the tappet on the wire, the movements of the parts being so 100 timed or accelerated that the fork leaves the tappet as soon as the pawl and ratchet clutch is thrown into operative condition. This single rotation of shaft 23 secures the feeding or dropping of the proper number 105 of kernels or seeds for a single hill at each side of the machine, as described below. When shaft 23 has completed this single revolution, the fork 25 co-acting with the single check wire is again in position to receive an impulse or initial movement from the next tappet. When the fork has reached this position, roller 49, under the influence of its downwardly-pulling spring 48^a, has traveled over the right-angle flanges 34, 115 see Fig. 22, struck the stop 36, thereby arresting the momentum of the moving parts, and then dropped into the seat 35, see Fig. 14, in so doing pushing the arm 40 over sufficiently to release pawl 38 from the 120 teeth of ratchet 30. When the flange 34 first strikes roller 49 the heavy arm 48, is raised against the action of spring 48^a and in so doing the momentum of the rotating parts is wholly or partially absorbed 125 or utilized in raising the arm, whereby the momentum is readily and easily gotten rid of. Casting 28 and the integral sprocket wheel 29 and ratchet 30 continue their constant and steady rotation, but the move- 130

ment of shaft 23 and its attached forks ceases, owing to the unclutching of the parts, that is, owing to the throwing of pawl 38 out of engagement with the ratchet 5 teeth. When one of the forks again strikes a tappet or button of the check row wire this operation is repeated, the initial movement of the fork by the tappet throwing the clutch 38-30 into operation again so that the power for the dropping or feeding of the kernels is derived from the axle of the machine rather than from the movement of the fork due to the engagement of the tappet therewith.

15 Each seed reservoir or compartment 22 is hinged on a bolt 57 which passes through a pair of ears 58 suitably mounted on the frame of the machine. At the bottom of its interior each compartment 22 has an upwardly-bowed spider 59, as shown in Fig. 2, to the central portion of which, and beneath the same on a bolt 60, is rotatably mounted a dome-shaped or convex agitator 61 having depending from its bottom face 25 a pair of parallel fingers 62. Also hinged on the bolt 57 is a ring 63 having at its bottom edge a circular inwardly-extended flange 64 on which rests and rotates a ring or annular seed plate 65 of substantially the same diameter as the internal diameter of ring 63 (Fig. 11) and notched at intervals around its periphery at 66 to provide cells or pockets each adapted to receive one seed or kernel of corn. In addition this seed 30 plate has projected inwardly four ears or lugs 67 (Fig. 4). Opposite its hinge, ring 63 has an aperture or hole 68 therethrough to allow the seeds or kernels to pass to the discharge chute or boot described below.

40 On the main frame is a substantially annular member 69 having a circular groove on its top surface within which fits a flat annular or round crown gear 70 having on its top face four projections 71 and on its 45 under face the gear teeth 72 meshing with the teeth of a pinion 73 (Fig. 9) forming part of a sleeve 74 loosely mounted on shaft 23 and having at its other end four ratchet teeth 75. In order to prevent the 50 crown gear 70 from rising, I fasten by bolts 76 to the ring 69 a segmental plate 77 which partially overlaps the top face of the gear, as is clearly indicated in Fig. 6.

Beneath each seed reservoir 22 and fixed 55 to shaft 23 by a set-screw 78, (Fig. 4) I provide a sleeve 79 having at one end a cam 80 and at its other end and overlying the teeth of ratchet 75 a pair of ears 81 between and to which is pivoted a pawl 82 60 having a tail 83, a spring 84 (Fig. 7) being provided for normally pushing the pawl or dog into engagement with the teeth of the ratchet.

In order to provide means for changing 65 the number of kernels or seeds fed to each

hill, I supply the following parts for the two feeding mechanisms: Slidable in suitable bearings is a shaft or rod 85 see Figs. 2, 3 and 8 having fixed thereto by a set-screw 86 a foot-lever 87 pulled downwardly by a spring 88 attached at one end to the lever and at the other end to a part of the frame. Fixed to the frame and adjacent to and below the lever is an upright plate 89 having on its top edge three notches 90, 91, and 92 into any one of which a tongue or rib 87^a (Fig. 14) on the under side of the lever may fit to hold the lever in fixed adjusted position and prevent shaft 85 from shifting longitudinally. Keyed or pinned to shaft 85 beneath each seed reservoir is a pawl releaser 93 which has a top curved or concave surface or track 94 substantially concentric to shaft 23, and at one side of the surface 94 is a similar but shorter curved surface 95. Each pawl-releaser 93 is fastened to shaft 85 in such a manner as to prevent its movement lengthwise the shaft, but it is permitted to have a slight rocking on the shaft. On the frame of the machine and on opposite sides of each releaser 95 see Fig. 8 are a pair of laterally-extended stops 96 and 97 see Fig. 7 against which are adapted to abut the shoulders 98 and 99 of the releaser to limit its turning on its shaft. The parts are so adjusted and positioned that when the rib 87^a is resting in notch 90 of plate 89 the curved surface 94 of each pawl-releaser 93 will be in the path of travel of the tail 83 of its pawl 100 82. Under these conditions, during a complete revolution of shaft 23 each pawl 82 will be in engagement with the teeth 75 of and turn its ratchet during one-half of the revolution, and during the other half of 105 the revolution the pawl will be held out of engagement with the ratchet teeth by the curved surface 94; consequently the bevel pinion will be turned only one-half a revolution. The feed plates actuated by the pinions under such conditions will feed two 110 kernels of corn to each hill.

If the rib 87^a of lever 87 is in notch 91 then the shorter curved surface 95 of each releaser or controller 93 will be in the path of travel of its pawl tail 83 instead of the curved surface 95. Under such conditions, during a single complete revolution of shaft 23 each pawl 82 is in operative engagement with the teeth 75 of its ratchet during three-quarters of a revolution and is maintained out of engagement during the remaining one-quarter revolution by the curved surface 95. This relation of parts causes three of the seed pockets 66 to be brought over 115 each of the discharge chutes and their contents ejected, instead of two pockets or cells as in the previous instance.

If the rib 87^a of the foot-lever 87 is in the notch 92 of the holding plate 89 then neither 120

of the curved surfaces 94 or 95 are in the path of travel of the tails of the pawls, so that a complete revolution of shaft 23 causes a complete revolution of the bevel pinions 73, resulting in a partial rotation of the seed plates sufficient to cause a feeding of four kernels to each hill.

During the rotation of shaft 23 each convex or crown agitator 61 is oscillated because of the coöperation of its cam 80 with the pair of fingers 62 between which it fits. This action of the agitator stirs up the kernels sufficiently to cause each of the cells or chambers 66 of the seed rings 65 to be filled with one of the kernels or seeds, sufficient space being allowed between the edge of the agitator and the side of casing 22 to permit the kernels to pass to their cells. As is obvious, edge or flat drop seed plates may be employed for feeding and delivering the kernels. To prevent more than one kernel or seed from becoming housed or seated in any of the recesses or pockets 66, I provide a fillet 68^a, see Fig. 11, at the junction of flange 64 with the rim of the holder 63, this fillet being extended around about one-third of the annular holder and being located so as to form a part of the bottom of the seed pockets 66. If more than one seed or kernel 30 attempts to lodge in any cell or pocket, the fillet causes one or more of them to project sufficiently above the pocket or cell so that it or they become dislodged by the other kernels of corn of the reservoir or compartment 35 and allow a single kernel to become properly seated in the pocket. The remaining two-thirds of the holder not provided with the fillet may have a flat smooth surface or may be slightly grooved or depressed at 63^b to 40 facilitate the retention of the kernels in the cells. Practically all of the pockets or cells are filled during the first third or half of the rotation of the seed plate so that there is no necessity of extending the fillet any 45 greater distance. The seed plate of course has to be beveled or chamfered to allow for the presence of the fillet.

The intermittent and variable rotation of the pinions 73 has been described above, and 50 it will be readily understood that such actuation of the pinions causes partial or step by step rotation of gears 70 and seed plates 65, the extent of rotation for each revolution of shaft 23 depending upon the position of foot-lever 87 and the pawl-releasers 93. The partial rotations of the gear rings 70 are 55 transmitted to seed plates 65 by means of the lugs 71 abutting against the similar lugs 67 on the inner edge of the seed rings. It 60 will, therefore, be understood that the seed rings are rotated intermittently an amount which may be varied at will, depending upon the position of lever 87, and owing to this adjustable travel or rotation of the seed 65 rings a variable number of seed cells or

chambers 66 are brought opposite the discharge openings 68 of rings 63 for each complete rotation or revolution of shaft 23. By leaving foot-lever 87 in adjusted position with its rib 87^a in any one of the notches of plate 89, a definite number of seeds or kernels will be deposited in each hill.

Opposite its hinge bolt 57 each spider 59 is provided with a hollow compartment 100 (Fig. 5), housed within which is a cell-filling spring-pressed plunger 101 and an ejector plunger 102 both sliding at an inclination through apertures in the top and bottom walls of the chamber. Plunger 101 is pressed downwardly by a spring 103 and caused to securely seat a seed or kernel of corn in each of the cells 66, the lower end of the plunger riding on the top surface of the seed ring 65. The ejector plunger 102 is also pushed downwardly by a spring 104, the lower end of the plunger being located above the discharge opening 68 and above the dropping chute described below. The lower portion of the plunger is adapted to enter each loaded cell or receptacle 66 as it comes beneath the same so as to positively eject the kernel of corn or seed from each cell when it is over the discharge chute.

Each seed reservoir 22 is provided with a downwardly-projected spring catch 105 (Figs. 4 and 15) adapted to project through the aperture 68 of ring 63 and underlie a portion of the ring, as indicated in Fig. 15, so that the casing 22 and the ring may be lifted together and turned simultaneously about the hinge bolt 57. In order to lock the parts down in position I provide the casing 22 with a projection 106 apertured to receive a bolt 107 having on its lower end a winged nut 108 intended to be brought to bear against the under surface of a bifurcated lug 109 between the projections of which the bolt fits.

Beneath the aperture 68 of ring 63 each annular member 69 has an opening 110 therethrough, beneath which is disposed the discharge chute 111 substantially rectangular in cross-section and having at its lower end a discharge mouth 112 at the heel of a runner or furrow opener 113, the forward end of which is supported by braces 114 fastened to the frame. At the top end of the discharge chute 111, pivoted on a transverse pin 115, and of substantially the same width as the passage through the discharge chute, is a valve lever 116 having an end 117 extended out of the chute through a suitable opening toward shaft 23, and having at its outer end a valve portion 118 adapted to close the opening beneath hole 110, as indicated in Fig. 15. Turning of this lever on its fulcrum is limited by a pin 119 extended transversely across the chute. A comparatively long arm or connecting rod 120 is pivoted to lever 116 at 121 and has near its top end a 125

lateral perforated boss 122, on one face a recess or depression 123, and at its lower end another recess 124. To form recess 123 the rod 120 is offset as shown. Pivoted at 125 at the lower end of the chute is a valve pocket or receptacle 126 of substantially the same width as the interior of the chute, and having an open top 127 and an open side 128, the other sides being closed. Pocket 126 and arm 120 are pivoted together at 129, the arm fitting between the two side walls of the pocket and closing the open side 128 when the parts are in the position shown in dotted lines in Fig. 12. A headed pin 130 passes through the axial aperture of boss 122, an encircling spring 131 normally pulling the head of the pin toward the arm 120. Between this head and the arm or rod 120 is a bar or intermediate valve 132 apertured 20 at its top end for the passage of the pin and bent or offset at 133 and 134 as indicated. A valve controller 135 lies against one exterior face of the chute, and has at one end an integral laterally-projecting pin 136, see Fig. 18, extended through aligned holes in the two sides of the chute and held in place by a cotter pin 137, the pin 136 forming the fulcrum for the controller 135. A coil spring 138 is fastened at one end to the pin 136, see Fig. 8, and at the other end to the eye or loop 139 of arm or rod 120. A pin 140 not quite so long as the pin 136 projects from the same side of the controller 135 at its other end. This pin 140 extends into the interior of the chute through a slot 141 in one side of the chute curved concentric to pin 136. As is clearly illustrated on the figures, the pin 140 lies between arm or rod 120 and bar 132 acting as a support on or over which bar 132 slides. The side of the chute has two holes 142 and 143 into either of which may fit the end of a slidable spring-pressed pin 144, having a head 145, housed within a boss 146 of the member 135 and spring-pressed toward the chute. As will be readily understood, pin 144 in one or the other hole maintains the valve controller in adjusted position. When the controller 135 is in the position shown in Fig. 15 with pin 144 in hole 142 the parts are adjusted for planting in hills, but when the controller is moved to the position shown in Fig. 16 with the pin in hole 143 the parts are ready for drilling.

In order to open and close the valves or pockets described, I provide means for turning lever 116 on its fulcrum, its movement being transmitted to the other parts through the connection shown and described. For this purpose I equip sleeve 79 with an arm 147 in such position that as shaft 23 and the sleeve 79 made fast thereto revolve, the arm 147 will come beneath the end 117 of lever 116, which is normally held down by the action of spring 138, the other or valve end 118 closing the passage through the top end of the chute. When the arm 147 lifts the end 117 of lever 116 the valve portion 118 moves downwardly, opening passage through the top of the chute. This turning of arm 147 on its pivot or fulcrum 115, as indicated in Fig. 15, pushes the connecting rod 120 downwardly, thereby turning the pocket 126 on its fulcrum 125 and opening the mouth thereof discharging previously received kernels or seeds. Assuming that the controller 135 is in the hill planting position shown in Fig. 15, that part of bar 132 between its offsets 133 and 134 as it descends slides on pin 140 and is pushed over so that the lower end of the bar contacts with a wall of the chute, forming therewith an intermediate deposit chamber which receives and temporarily holds the kernels or seeds passing through the upper valve. As soon as the arm 147 passes by the end of lever 116 spring 138 comes into action so as to close the upper valve 118 and the lower pocket or valve 126. This upward movement of the parts causes the spring-pressed bar 132 to recede from the wall of the chute because the part thereof below offset 134 rides on pin 140 so that the kernels or seeds held in the intermediate deposit chamber are dropped into the lower pocket, which is at the time closed ready for discharge into a hill on the succeeding actuation of lever 116. It should be understood that the seeds which pass through the upper valve are temporarily retained in the intermediate deposit and afterward delivered to the heel valve or pocket for subsequent discharge into a hill.

For drilling, the controller 135 is swung downwardly and held in its new position by the spring pin 144 fitted in the hole 143. When in this position the pin 140 fits in the recess 123 of the connecting rod 120 and holds the same down against the tension of the spring, as indicated in Fig. 16, in such position that the top and lower valves are open and the end 117 of lever 116 is out of the path of travel of arm 147. It will also be noticed that the passage through the chute is open its complete length, the bar 132 lying against the connecting rod 120 under the influence of its spring 131 because of the new position of pin 140. It will be apparent, therefore, that as soon as the seeds are ejected or dropped out of the seed plate, they fall through the chute to the ground without stopping. In order, however, to make the feed of the seeds or kernels continuous, rather than intermittent as is required for hill planting, I rotatably mount on the frame a short shaft 148 see Fig. 3 having at one end an actuating handle 149 and at its other end an arm or cam 150 which during its partial rotation to bring it to dead center is adapted to engage a depending finger 151 of the casing 50 and 130.

push the same along the rod 47 against the action of springs 53 and 48^a see Figs. 2, 3 and 14. This sliding movement of the casting 50, its integral arm 48, and attached 5 roller 49 moves the latter out of the path of travel of the casting 33 and the tail 40 of pawl 39, so that the pawl is in constant engagement with one of the teeth of ratchet 30, and the continuous rotation of ratchet 10 30 is transmitted to shaft 23 so that the same revolves continuously, no tappets or buttons on a check wire being required for an initial movement. If the feed of seeds or kernels is to be continuous, the rib 87^a of 15 the foot lever 87 should be in notch 92 so that the continuous and uninterrupted turning of shaft 23 causes a like continuous rotation of the seed plate and a steady feeding or dropping of seeds. If desired, however, 20 the drilling action may be such as to cause intermittent movement of the seed plates, the interval of rest being variable through adjustment of the connecting mechanism between the plates and actuating shaft. An 25 intermittent drilling action is advantageous in the planting of cotton. Seed is thus saved and chopping out of growing plants is obviated.

The planter, as illustrated, has two seed-dropping devices on opposite sides of the machine actuated by the common shaft 23, and ordinarily the number of seeds or kernels dropped in one row of hills at one side of the machine would not differ from that dropped on the other side. If, however, it is desired to plant or drop different numbers of kernels or seeds per hill at the two sides of the machine, one of the pawl-releasers 93 (see Fig. 8) may be slid along rod 85 and 30 held in its new position by the cotter pin 93^a passing through a perforation through the hub or sleeve of arm 93 and one of the holes 85^a through the rod 85, of which one or more may be provided. By thus changing 35 the position of one of the releasers, thereby modifying the relation of the curved pawl-releasing surfaces of the pair of releasers, the dropping of seeds or kernels on the two sides of the machine may be made 40 anything desired, for example, two kernels on one side and three on the other, or three on one side and four on the other.

It will be noted that the arm 48 and its roller 49 during the rotation of the shaft 50 first stop or arrest the momentum of the moving parts by the striking of the roller against stop 36 and then under the action of spring 48^a the roller drops into the seat 35 holding pawl 38 out of engagement with the ratchet teeth 30. When one of the forks 55 strikes a tappet or button of the check row wire, the shaft, casting 33, and the pawl 38 pivoted thereto begin to rotate, arm 48 and its roller 49 remaining substantially stationary. As soon as the tail 40 of pawl 38

has passed over or is freed from the roller 49, the pawl at once engages one of the teeth of the ratchet so that the further rotation of the shaft and parts actuated thereby is carried on by the chain and sprocket connection 29, 31 with the axle of the machine. Owing to this construction, the release of the pawl from the roller is accomplished with but little strain on the tappet of the check row wire and because of the positive 70 stop by the roller of the moving parts by engagement with stop shoulder 36 there is no tendency for the rotating parts to fly by without coming to a complete standstill.

Although I have shown and described a 80 machine which will plant two, three, or four seeds or kernels to a hill, to those skilled in this art it will be apparent that the machine may be modified to plant any desired number without departing from the substance 85 and essence of my invention; and that the range of variation of the numbers of kernels per hill may be readily modified.

In order that the operator may know how the machine is working, each discharge 90 chute may be supplied or furnished with a transparent window 152 preferably just above the intermediate deposit, but the device works so satisfactorily and reliably that such a window or peep-hole is hardly necessary.

The provision of the handle or arm 54, see Fig. 2, working in slot 55 is not absolutely requisite, but when it is shifted or turned so that if member 50 were slid on rod 47 it would strike the abutment 56 it acts as a safeguard to prevent arm 48 from being moved into drilling position when hill planting only is contemplated.

Although I have illustrated and described 100 my invention in connection with a machine of the rotary fork type having but a single shaft, it will be apparent to those skilled in the art that it may be used readily and advantageously in other styles of machines, 110 such as, for example, those that have the forks on shafts separate and distinct from the seed plate operating shaft.

Many modifications in the structure herein disclosed may be made without sacrificing the advantages of my improved construction and without departing from the substance 115 of my invention as defined and outlined in the appended claims.

I claim:—

1. In a seed-planter, the combination of a 120 movable seed-plate provided with recesses adapted to accommodate seeds or kernels and discharge them at a definite point in the movement of said plate, an intermittently-actuated operating means, connecting means between said operating means and seed-plate whereby during each actuation of said operating means said seed-plate is moved to successively bring a number of said recesses into 125 130

- discharging position each delivering its contents, and controlling means adapted to break the operative connection between said operating means and seed-plate at different 5 points in the actuation of the latter whereby to vary the number of seeds or kernels delivered to each hill.
2. In a seed-planter, the combination of a rotary seed-plate provided with recesses 10 adapted to accommodate seeds or kernels, a discharge chute, a rotary shaft intermittently operated for revolving said seed-plate to bring a number of said recesses into communication with said discharge chute successively each discharging its contents into 15 said chute, means connecting said rotary shaft with said seed-plate, and controlling means adapted to break the operative connection between said rotary shaft and seed-plate at different points in the actuation of 20 the latter whereby to vary the number of seeds or kernels delivered to each hill.
3. In a seed-planter, the combination of a rotary seed-plate provided with recesses 25 adapted to accommodate seeds or kernels and discharge them at a definite point in the movement of said plate, an intermittently-actuated rotary operating shaft adapted to revolve said seed-plate to bring a number of 30 said recesses successively into discharging position each delivering its contents, a clutch between said shaft and seed-plate, and controlling means to render said clutch inoperative at different points in the actuation of 35 said seed-plate whereby to vary the number of seeds or kernels delivered to each hill.
4. In a seed-planter, the combination of a rotary seed-plate provided with recesses 40 adapted to accommodate seeds or kernels and discharge them at a definite point in the movement of said plate, an intermittently-actuated operating shaft adapted to revolve said plate to bring a number of said recesses successively into discharging position each 45 delivering its contents, a clutch between said shaft and seed-plate comprising a ratchet wheel and a pawl normally engaging a tooth of said ratchet wheel, and controlling means to move said pawl and maintain it out of engagement with said ratchet at different points in the actuation of 50 said seed-plate whereby to vary the number of seeds or kernels delivered to each hill.
5. In a seed-planter, the combination of a rotary seed-plate provided with recesses 55 adapted to accommodate seeds or kernels and discharge them at a definite point in the movement of said plate, an intermittently-actuated operating shaft adapted to revolve said seed-plate to bring a number of said recesses successively into discharging position each delivering its contents, a clutch between 60 said shaft and seed-plate comprising a ratchet wheel and a pawl rotatable with said shaft and normally engaging a tooth of 65 said shaft and
- said ratchet, and controlling means with pawl-releasing tracks of different lengths adapted to be projected singly into the path of travel of said pawl to move the latter and maintain it out of engagement with said 70 ratchet at different points in the actuation of said seed-plate whereby to vary the number of seeds or kernels delivered to each hill.
6. In a seed-planter, the combination of a rotary seed-plate provided with recesses 75 adapted to accommodate seeds or kernels and discharge them at a definite point in the movement of said plate, an intermittently-actuated operating shaft adapted to revolve said seed-plate to bring a number of said recesses successively into discharging position each delivering its contents, a clutch between 80 said operating shaft and seed plate comprising a ratchet-wheel and pawl having a tail rotatable with said shaft and normally engaging a tooth of said ratchet-wheel, and 85 slideable controlling means with pawl-releasing tracks of different lengths adapted to be projected singly into the path of travel of the tail of said pawl to move said pawl and maintain it out of engagement with said ratchet during varying portions of the intermittent-actuations of said operating shaft whereby to vary the number of seeds or kernels delivered to each hill. 90
7. In a seed planter, the combination of a plate provided with seed cells, a shaft for moving said plate to discharge seed from said cells, a member rotated by power derived from the ground wheels, a freely movable clutch element between said shaft and member movable transversely with respect to said shaft into engagement with said member, means on said shaft adapted to be operated by a tripping device to impart initial movement to said shaft, such initial movement rendering the clutch element effective to continue the movement of the shaft, and means to release said clutch element and stop the momentum of the moving parts when the 95 clutch element is released. 100
8. In a seed planter, the combination of a seed plate provided with recesses adapted to accommodate seeds or kernels, a discharge chute, a shaft for moving said seed plate to bring a number of said recesses into communication with said discharge chute successively, each delivering its contents into said chute, a member rotated by power derived from the ground wheels, a clutch between 110 said shaft and member, a fork on said shaft adapted to coöperate with the tappets of the check row wire and by an initial turning of said shaft render said clutch operative to impart a full revolution to said shaft, means to release said clutch, an arm pivotally connected to a fixed part, and means connected to a moving part and positioned to lift said arm to stop the momentum of the moving parts when the clutch is released. 115
- 120
- 125
- 130

9. In a seed planter, the combination of a seed dropping or feeding mechanism, a shaft for operating said mechanism, a fork on said shaft adapted to coöperate with the tappets or buttons of the check row wire, a member rotated by power derived from the ground or carrying wheels, a freely movable clutch element between said member and shaft movable transversely with respect to said shaft into engagement with said member, means to render said clutch element operative by an initial partial rotation of said shaft caused by the engagement of a tappet on the check row wire with said fork to impart a full revolution to said shaft, and means to arrest the momentum of the shaft, fork and seed feeding mechanism and render said clutch element inoperative when said shaft has completed its rotation.
10. In a seed planter, the combination of a seed-dropping or feeding mechanism, a shaft for operating said mechanism, a fork on said shaft adapted to coöperate with the tappets or buttons of a check row wire, a member rotated by power derived from the ground or carrying wheels, a clutch between said member and said shaft, a stop arm rotatable with said shaft and having mounted thereon one of the elements of said clutch, and means co-acting with and in the path of travel of said stop arm and clutch element permitting an initial movement of said shaft by the engagement of one of the check row wire tappets with said fork to render said clutch operative, said means by engagement with said stop arm arresting the momentum of the shaft, fork, and seed-feeding mechanism and by coöperation with said clutch element rendering the clutch inoperative when the shaft and fork have completed their revolution.
11. In a seed planter, the combination of a seed-dropping or feeding mechanism, a shaft for operating said mechanism, a fork on said shaft adapted to coöperate with the tappets or buttons of a check row wire, a member rotated by power derived from the ground or carrying wheels, a pawl and ratchet clutch between said member and said shaft, a stop arm rotatable with said shaft and having mounted thereon the pawl of said clutch, and means co-acting with and in the path of travel of said stop arm and pawl permitting an initial movement of said shaft by the engagement of one of the check row wire tappets with said fork to permit said pawl to engage a tooth of said ratchet, said means by engagement with said stop arm arresting the momentum of the shaft, fork, and said feeding mechanism and by coöperation with said pawl rendering the clutch inoperative when the shaft and fork have completed their revolution.
12. In a seed planter, the combination of a seed -dropping or feeding mechanism, a shaft for operating said mechanism, a fork on said shaft adapted to coöperate with the tappets or buttons of a check row wire, a member rotated by power derived from the ground or carrying wheels, a stop arm rotatable with said shaft and having mounted thereon a clutch element, and a movable spring-actuated clutch-controlling arm co-acting with and in the path of travel of said stop arm and clutch element permitting an initial movement of said shaft by the engagement of one of said check row wire tappets with said fork to render said clutch operative, said clutch-controlling arm by engagement with said stop arm arresting the momentum of the shaft, fork, and seed-feeding mechanism and by coöperation with said clutch element rendering the clutch inoperative when the shaft and fork have completed their revolution.
13. In a seed planter, the combination of a seed-dropping or feeding mechanism, a shaft for operating said mechanism, a fork on said shaft adapted to coöperate with the tappets or buttons of a check row wire, a member rotated by power derived from the ground or carrying wheels, a stop arm rotatable with said shaft and having mounted thereon a clutch element, a movable spring-actuated clutch -controlling arm co -acting with and in the path of travel of said stop arm and clutch element permitting an initial movement of said shaft by the engagement of one of said check row wire tappets with said fork to render said clutch operative, said clutch-controlling arm by engagement with said stop arm arresting the momentum of the shaft, fork, and seed-feeding mechanism and by coöperation with said clutch element rendering the clutch inoperative when the shaft and fork have completed their revolution, and means to shift said clutch-controlling arm out of the path of travel of said stop arm and clutch element during drilling.
14. In a seed planter, the combination of a seed-dropping or feeding mechanism, a shaft for operating said mechanism, a fork on said shaft adapted to coöperate with the tappets or buttons of a check row wire, a member rotated by power derived from the ground or carrying wheels, a pawl and ratchet clutch between said member and said shaft, a stop arm rotatable with said shaft and having mounted thereon the pawl of said clutch, and a pivoted spring-actuated clutch-controlling arm co-acting with and in the path of travel of said stop arm and pawl permitting an initial movement of said shaft by the engagement of one of the check row wire tappets with said fork to render said clutch operative, said clutch-controlling arm by engagement with said stop arm

arresting the momentum of the shaft, fork, and said feeding mechanism and by co-operation with said pawl rendering the clutch inoperative when the shaft and fork have completed their revolution.

15. In a seed planter, the combination of a seed-dropping or feeding mechanism, a shaft for operating said mechanism, a fork on said shaft adapted to co-operate with the tappets or buttons of a check row wire, a member rotated by power derived from the ground or carrying wheels, a stop arm rotatable with said shaft, said arm having mounted thereon a clutch element, and being equipped with a right-angle track, a pocket or recess at the lower end of said track, and a stop shoulder, and a pivoted spring-actuated clutch-controlling arm co-acting with and in the path of travel of said right-angle flange, stop shoulder, and clutch element permitting an initial movement of said shaft by engagement with one of the check row wire tappets with said fork to render said clutch operative, said clutch-controlling arm by engagement with said stop shoulder arresting the momentum of the shaft, fork, and seed feeding mechanism, and by co-operation with said clutch element rendering the clutch inoperative when the shaft and fork have completed their revolution.

16. In a seed-planter, the combination of a plurality of movable seed-plates each provided with recesses adapted to accommodate seeds or kernels and discharge them at a definite point in the movement of the plate, an intermittently-actuated operating means, connecting means between said operating means and each of said seed-plates whereby during each actuation of said operating means each seed-plate is moved to successively bring a number of its recesses into discharging position each delivering its contents, and controlling means operable during the actuation of the machine and adapted to break the operative connections between said operating means and seed-plates at different points in the actuation of the latter whereby to vary the number of seeds or kernels delivered to each hill.

17. In a seed-planter, the combination of a plurality of seed-plates each provided with recesses adapted to accommodate seeds or kernels, a discharge chute for each of said seed-plates, means to intermittently move said seed-plates to bring a number of said recesses into communication with said discharge chute successively each delivering its contents to its chute, said means including an actuating shaft common to all of said seed-plates, and a single controlling means operable during the actuation of said machine to simultaneously break the connection between said actuating shaft and all of

said seed-plates at different points in the actuation of the latter whereby to vary the number of seeds or kernels delivered to the hills.

18. In a seed planter, the combination of a pair of seed-feeding mechanisms each adapted to plant a predetermined number of seeds or kernels per hill, an adjusting means to simultaneously vary the number of seeds or kernels delivered per hill by both of said seed-feeding mechanisms, and another adjusting means to vary the number of seeds or kernels fed by one of said feeding mechanisms.

19. In a seed-planter, the combination of a rotary seed-plate provided with recesses adapted to accommodate seeds or kernels and discharge them at a definite point in the movement of said plate, a shaft for rotating said plate, driving means for operating said shaft, a clutch between said driving means and shaft, means to throw said clutch out of action at the completion of each revolution of said shaft, a fork mounted on said shaft and co-acting with the tappets of a check-row wire to give the shaft its intermittent initial movements to render said clutch active thereby permitting said driving means to complete the revolution of said shaft and fork, connecting means between said shaft and seed-plate, whereby during each actuation of said shaft said seed-plate is rotated to successively bring a number of said recesses into discharging position each delivering its contents, and controlling means adapted to break the operative connection between said shaft and seed-plate at different points in the actuation of the latter whereby to vary the number of seeds or kernels delivered to each hill.

20. In a seed-planter, the combination of a rotary seed-plate provided with recesses adapted to accommodate seeds or kernels and discharge them at a definite point in the movement of said plate, a shaft for intermittently rotating said plate, driving means for operating said shaft, a clutch between said driving means and shaft, means to throw said clutch out of action at the completion of each revolution of said shaft, a fork mounted on said shaft co-acting with the tappets of a check-row wire to give the shaft its intermittent initial movements to render said clutch active, thereby permitting said driving means to complete the revolution of said shaft and fork, a second clutch between said shaft and seed-plate by means of which said shaft is adapted to successively bring a number of said recesses into discharging position each delivering its contents, and adjusting and controlling means governing the operation of said second clutch and adapted to vary the number of seeds or kernels planted per hill.

21. In a planter, the combination with a seed-dropping plate, of continuously operating mechanism from which said plate is operated by connecting mechanism, said connecting mechanism comprising a part adapted to be put into engagement with said continuously operating devices, to give said part a predetermined amount of movement at each actuation, and a further freely movable part adapted to be connected with said seed plate to give the same varying amounts of movement. 65
22. In a planter, the combination with a seed-dropping plate, of a continuously operating mechanism from which said plate is actuated by suitable connections, said connections comprising a part adapted to be operatively connected with said continuously operating mechanism to give said part a certain predetermined amount of movement, and a further part adapted to be connected with the seed plate for the whole or a part of the predetermined movement. 70
23. In a planter, the combination with a seed dropping plate, of continuously operated mechanism and connections for operatively connecting said continuously operating mechanism and said seed plate, said connections including a part adapted to be intermittently put into engagement with said continuously operating mechanism, to give said part a certain predetermined amount of movement, and a further part adapted to be connected with said seed plate during the whole or a part of the period of said predetermined movement. 75
24. In a planter, the combination with a seed dropping plate, of a continuously operating power applying mechanism therefor, a connecting device interposed between said power applying mechanism and said plate, provided with a movable part connecting said device with the power mechanism to effect the same predetermined movement of said connecting device at each operation, and a second movable part for connecting said device with the seed plate for imparting a variable movement thereto and controlling devices for throwing said second movable part out of operative position for different periods in the predetermined operation of said connecting device. 80
25. In a planter, the combination with a seed dropping plate, of a continuously operating mechanism and connections for operatively connecting said continuously operating mechanism and said plate, said connections comprising a part adapted to be connected with said continuously operating mechanism to give said part a certain predetermined amount of movement, and a further part adapted to be connected with said seed plate for varying periods during said predetermined movement whereby the said seed plate is connected with said continuously operating mechanism during the whole or a part of said predetermined movement. 85
26. In a planter, the combination with a seed dropping plate, of continuously operating mechanism and connections for operatively connecting said continuously operating mechanism and said seed plate, said connections comprising a part adapted to be thrown into engagement with said continuously operating mechanism to give said part a certain predetermined amount of movement, and a further part adapted to be connected with the said seed plate for the whole of said predetermined movement or to be disconnected with said plate during a part of said predetermined movement to give varying amounts of movement to the seed plate. 90
27. In a planter, the combination with a seed dropping plate, of continuously operating mechanism and connections between the two, said connections including a clutch adapted to be connected with said continuously operating mechanism to give the clutch a predetermined amount of movement, said clutch being also adapted to be connected with said seed plate for the whole or part of the predetermined movement of the clutch, and means for controlling the connection between said clutch and seed plate. 95
28. In a planter, the combination with the seed dropping plate, of continuously operating mechanism including a ratchet wheel, a pawl adapted to be thrown into engagement with said ratchet and to be disengaged therefrom after having been moved a predetermined distance, and means for connecting said pawl with said seed plate for the whole or part of its movement. 100
29. In a planter, the combination with the seed dropping plate, of a continuously operating mechanism including a ratchet wheel, a clutch comprising a body carrying two pawls, one of said pawls adapted to be thrown into engagement with said ratchet to be moved a certain predetermined distance, and the other pawl adapted to be thrown into connection with said seed dropping plate during the whole or a part of the predetermined movement of said pawl. 105
30. In a planter, the combination with a seed dropping plate, of a disk provided with a series of projections operatively connected with said seed plate, of a pawl normally engaging a projection of said disk to actuate the said disk and said plate, of a series of movable cams, and means for moving said cams independently into and out of position to engage said pawl to release said pawl from engagement with said disk. 110
31. In a planter, the combination with the seed dropping plate, of a disk operatively

- connected therewith and provided with a series of projections, a pawl normally engaging a projection of said disk, means for actuating said pawl, a series of movable cams adapted to be brought into position to engage said pawl, each cam adapted to disengage said pawl from one of the projections of said disk and pass over the same, and means for moving one or more of said cams into position to engage said pawl. 65
32. In a planter, a seed shaft, a seed dropping element, a constantly rotating mechanism on the seed shaft, means for connecting the constantly rotating mechanism to the seed shaft at predetermined periods for imparting a complete revolution to the latter, and adjustable means for connecting the shaft and seed dropping element to impart more or less movement to the latter 70 during each revolution of the shaft. 75
33. In a planter, a seed plate, a rotatable driving clutch actuated at predetermined intervals through 360° of movement, and adjustable means connecting the clutch and seed plate for driving the latter through variable degrees of movement. 80
34. In a seed plate, a seed shaft, a seed plate on each end thereof, an intermittently operating clutch for imparting a complete 85 revolution to the seed shaft, and adjustable means between each seed plate and the shaft for imparting variable degrees of movement to the plates. 90
35. In a seed planter, a seed shaft, seed plates at each end thereof, an intermittently operating clutch for imparting a complete revolution to the seed shaft, adjustable connecting mechanism between each seed plate and the shaft for imparting variable 95 degrees of movement to the plates, and unitary controlling means for both of said connecting mechanisms. 100
36. In a seed planter, ground wheels, a frame carried thereby, a driver's seat on said frame, a furrow opening frame carried at the forward end of the wheel frame, a shaft extending transversely of said furrow opening frame, a hopper at each end of the shaft on the furrow opening frame, seed 105 dropping mechanism in said hoppers, a clutch carried on the shaft and receiving power from the ground wheels, means for operating the clutch intermittently to give the shaft a predetermined movement at each 110 operation thereof, connecting mechanism between each end of the shaft and the adjacent seed dropping mechanism, and means operable from the seat for adjusting said connecting mechanism to vary the distance 115 through which the seed dropping mechanism is moved. 120
37. In a seed planter, a seed dropping element, a revolute device having a fixed intermittent movement, and connecting mech- 125
- anism capable of imparting more or less of said movement to the seed dropping element. 65
38. In a seed planter, a seed dropping element, driving mechanism, and connecting mechanism therefor comprising a ratchet device, a pawl, a cam mechanism to engage with the pawl and permit it to pass over one or more notches in said ratchet, and means for moving said cam to vary the extent of engagement. 70
39. In a planter, a seed dropping element, a rotatable shaft therefor, a fork fixed to said shaft, a constantly rotating member loose on said shaft, a clutch member rotatable with said shaft and movable transversely with respect thereto into engagement with said constantly rotating member by an initial movement of said fork, and means for disconnecting said clutch from the constantly rotating member at the end 85 of a full revolution. 90
40. In a planter, a seed plate, driving mechanism operable intermittently through a fixed degree of movement, and connecting mechanism between the seed plate and driving mechanism for actuating the former at a constant angular velocity through variable degrees of movement. 95
41. In a planter, a seed dropping element, an actuating shaft therefor, constantly rotating mechanism for driving said seed shaft, a clutch member on said shaft in position to engage with said constantly rotating mechanism, a check fork fixed to said shaft and normally projected downward 100 whereby an initial pull on said fork operates to connect said clutch member with the constantly rotating mechanism for a predetermined period, and a trip device carried in the path of said clutch member to disengage the latter from the constantly rotating mechanism at the end of a full revolution. 105
42. In a seed planter, a seed dropping element, driving means controllable by check row mechanism to operate intermittently 110 and adapted to operate constantly when the check row mechanism is discontinued, and adjustable connecting means between the seed dropping element and the driving mechanism. 115
43. In a convertible check row and drill planter, a seed dropping element, driving mechanism capable of intermittent or continuous operation, and connecting means between the driving mechanism and seed dropping element, said connecting mechanism being adjustable to vary the quantity of seed delivered by the seed dropping element when the driving mechanism is operated in either manner. 120
44. In a seed planter, a seed dropping element, means whereby the seed dropped therefrom may be drilled comprising actuati- 125

ing mechanism for said dropping element automatically imparting successive periods of movement thereto, and means for adjusting said actuating mechanism to vary the periods of movement.

45. In a seed planter, carrying wheels, a main frame, a driver's seat on said frame, a seed hopper carried by said frame in a position remote from said driver's seat, a seed dropping element in said hopper, means whereby the seed dropped therefrom may be drilled comprising actuating mechanism driven continuously by the carrying wheels, said actuating mechanism being capable of automatically imparting successive periods of movement to the seed dropping element, and means operable from the driver's seat
- 10
- 15

for adjusting said actuating mechanism to vary the periods of movement.

46. In a seed planter, a seed dropping element, driving mechanism therefor, means whereby the seed dropped by said element may be drilled comprising a make and break connecting mechanism between the driving mechanism and the seed dropping element 20 operating to automatically suspend movement of said seed dropping element, and means for adjusting said connecting mechanism to vary the intervals of rest. 25
